(57) **CLAIM**

We claim the ornamental design for a suction nozzle for a floor care appliance, as shown and described.

DESCRIPTION

FIG. 1 is a perspective view of a suction nozzle for a floor care appliance showing our new design;

FIG. 2 is a top view thereof;

FIG. 3 is a front side view thereof; and,

FIG. 4 is a cross-sectional view thereof taken along line 4—4 of FIG. 2.

The portion shown in dashed lines is for illustrative purposes only and forms no part of the claimed design.
